COMBINATION BIRD FEEDER, PLANTER OR THE LIKE

Donald G. Clever, San Francisco, Calif., assignor to
Proen Products Co., a corporation of California

Filed Dec. 26, 1961, Ser. No. 68,064

Term of patent 7 years

(Cl. D31—2)

FIG. 1.

FIG. 2.

FIG. 3.

FIGURE 1 is a side elevational view of a combination bird feeder, planter or the like showing my new design;
FIGURE 2 is a top plan view thereof; and
FIGURE 3 is a front elevational view thereof.

I claim:

The ornamental design for a combination bird feeder, planter or the like, as shown.
